POCKET LOCK FOR A BILLFOLD

Woodrow Winston, 515 Walden Ave.,
Buffalo, N.Y. 14211

Filed Aug. 19, 1974, Ser. No. 498,544

Term of patent 14 years

Int. Cl. D3—99

U.S. Cl. D87—2 R

Fig. 1.

Fig. 2.

Fig. 3.

Fig. 4.

Fig. 5.

FIG. 1 is a front elevational view of a pocket lock for a billfold showing my new design;

FIG. 2 is a top plan view;

FIG. 3 is a bottom plan view;

FIG. 4 is a rear elevational view; and

FIG. 5 is a right side elevational view, the left side being a mirror image thereof.

I claim:

The ornamental design for a pocket lock for a billfold, as shown and described.
